UNITED STATES PATENT OFFICE.

JAY CRUMPACKER, OF McPHERSON, KANSAS.

AUTOMATIC NAILING-HAMMER.

1,348,544.

Specification of Letters Patent.

Patented Aug. 3, 1920.

Application filed February 12, 1920. Serial No. 358,182.

To all whom it may concern:

Be it known that I, JAY CRUMPACKER, a citizen of the United States, residing at McPherson, in the county of McPherson and State of Kansas, have invented certain new and useful Improvements in Automatic Nailing-Hammers, of which the following is a specification.

The invention has for an object to effect improvements in magazine hammers, aiming to simplify the construction thereof, and improve the function of such devices, as well as to produce new and novel structure attaining the ends in view. It is an aim to provide a device of this character which may be manipulated with one hand to feed and hold nails in a position upon a hammer whereby they may be started in wood or the like, and the driving of such nails completed with the same implement, with speed and rapidity. It is also a purpose to enable the embodiment of the necessary mechanism in such light and compact form that the combined hammer and magazine parts may be readily manipulated and will not be objectionable because of clumsiness or peculiarity in form. It is also an aim to provide an appliance of this character which may be readily and quickly taken down for cleaning or adjustment without requiring expert mechanical knowledge or special tools.

It is a special purpose to improve the nail feeding means, in a trigger device by which nails may be moved into position for driving at will.

Additional objects, advantages and features of invention will appear from the following disclosure including drawings, wherein,

Figure 1 is an elevational view of a lathing and shingling hatchet constructed in accordance with my invention.

Fig. 2 is a similar view of the main body part of the device, with the operating and covering element removed.

Fig. 3 is a cross sectional view of the head.

Fig. 4 is an inner side elevation of the cover plate and trigger device.

Fig. 5 is a longitudinal sectional view of the device.

Fig. 6 is a similar view in a plane at right angles to that in which Fig. 5

is taken, showing only the handle and nail feed portion of the device.

55.

Fig. 7 is a cross section of the handle portion, looking rearwardly.

Fig. 8 is a detail of the feed block, and face block removed.

Fig. 9 is a view similar to Fig. 6, showing a further embodiment of the invention.

Fig. 10 is a cross section of the head of the second embodiment, from the direction of the handle.

Fig. 11 is a view of the second embodiment showing the parts open for inspection.

Fig. 12 is an end view of the handle,

Fig. 13 is a plan view of the hammer face.

There is illustrated a magazine hammer comprising a handle body portion 10 which may be formed of any suitable material, as aluminum, or wood, and carried thereby there is a face block 11 and blade 12, each of which may be formed of such metal as customarily employed in the art of hammer making. The outer part of the handle portion is hollow, to form a reservoir 13, the inner end of which is reduced so as to discharge into a recess 14 formed in the handle and opening on the left face of the handle body when the hammer is in position for engagement of its face upon a nail to be driven. This recess 14 is rectangular in form, and opens on the under side of the handle as well as upon the left side, extending from a point near the middle of the handle, to the end thereof, extending through what would be the poll of the hammer head in ordinary cases. This recess is limited by the block or extension 15 from its upper side in the poll portion of the device, and is closed at its outer end by a plate portion 16 which may be secured to the block 15 by screws or made integral with the handle body, if found preferable. The handle 10 is approximately 70

rectilinear in form at and adjacent the head portion of the hammer. The outer handle portion may be swelled or otherwise formed to afford a comfortable grip for the user. Engaged in the recess 14, but stopping short 75

of its upper side so as to form a nail passage 14', there is a feed block 17, having flange portions 18 secured by screws upon the plate 16 and the handle body at the inner end of

the recess 14 respectively. The block 17 is 80

bifurcated by the formation of a slot 19

85.

rectilinear in form at and adjacent the head portion of the hammer. The outer handle portion may be swelled or otherwise formed to afford a comfortable grip for the user. Engaged in the recess 14, but stopping short 85

of its upper side so as to form a nail passage 14', there is a feed block 17, having flange portions 18 secured by screws upon the plate 16 and the handle body at the inner end of

the recess 14 respectively. The block 17 is 90

bifurcated by the formation of a slot 19

therein opening on the forward end of the block, the lower furcation 20 stopping short of the plate 16, while the upper one abuts the plate snugly, at the part where the flange 18 is formed to engage over the plate 16. The channel 14' is closed at the outer side by a plate 21, which may be of metal or glass, the latter enabling an operator to quickly observe whether nails are being properly fed through the device. The reservoir 13 opens on the rear end of the handle, and is closed by a pivoted plate 22 of a suitable nature. By this structure nails may be introduced into the reservoir 13. By tilting the hammer downwardly toward its forward end nails are caused to feed into the channel 14', the forward part of the reservoir being gradually tapered so that the nails become alined with the axis of the handle, and after passing through the channel 14' with the face of the hammer turned downwardly, the shanks of the nails fall between the furcations of the block 17, their heads hanging upon the upper edges of the block which are smoothly finished and rounded so that the nails supported upon their heads slide easily toward the forward part of the hammer. By the shortening of the portion 20 of the block 17, a lateral passage 23 is formed leading from the slot 19, so that when the hammer is positioned with its left side downwardly nails feeding through the block 17 may pass laterally toward the left side of the hammer.

35. The body of the handle 10 at the forward lower part of the recess 14 stops short of the plate 16 so as to form a continuation of the passage 23, and reciprocable in a suitable recess in the right hand side of the hammer 40 when the face is presented downwardly there is a T-shaped plate 24, spring-pressed so as to lie normally toward the forward end of the hammer and having a nail-shaped slot 25 therein then alined with the passage 23, and reciprocable for movement of the slot 25 inwardly of the passage 23 in a direction longitudinally of the hammer handle. The head portion 26 of the plate 24 projects into the face block of the hammer, which is suitably formed to permit this as indicated clearly at 45 27 in Figs. 3 and 8. The plate 24 is retained in the handle by means of a cover plate 28 suitably set flush in the handle; and the plate 24, its spring and the cover plate may be removed as a unit assembly, as shown in Fig. 4, by reason of the construction followed. The stem portion 29 of the plate 24 extends longitudinally toward the rear part of the handle, and is formed with a lateral lug 30 engaging in an extension 31 of the recess in which the plate is slidably fitted, the extension 31 being of greater dimension longitudinally of the handle than the lug, so as to permit longitudinal reciprocation of the plate. Formed

in the plate in a position to aline with the slot 25 when the trigger plate is at the inner limit of its movement, there is a nail discharging slot 32, the ends of which are of just sufficient width to permit easy movement of a nail shank therein, while the intermediate part of the slot is enlarged to considerably more than the diameter of a nail head, so as to permit the movement of nail heads through this wider portion. The stem of the trigger plate is centrally slotted as at 33, to accommodate therein for free movement of the trigger plate, a helical spring 34 one end of which is connected to the rear part of the stem of the plate, while the other is engaged upon a transverse pin 35 in the cover plate 28. The cover plate is recessed to permit the major portion of the spring 34 to lie therein, and the trigger plate is drawn closely against the cover plate so as to hold the trigger assembly together.

In the use of this form of the device, after a quantity of nails have been introduced into the handle and passed through the feed slot to the passage 16, when the hammer is held with the right side presented downwardly a nail will fall through the passage 16 into the slot 25 of the trigger plate, and by drawing upon the trigger a nail may be drawn rearwardly until it lies over the passage 32. In this position, the nail will be unsupported except where its head portion rests upon the sides of the slot 32, the head being too large to pass through the narrow end portions of this slot. Consequently the point of the shank will fall through the slot and the nail hangs suspended at the narrow end of the slot. The material of the cover plate is slightly recessed at 37 in this part so that the nail head will drop below the plane of the trigger plate, whereby when the trigger is released the flat portion 36 of the trigger plate will move over the slot 32. The nail may then be driven by delivering one blow with sufficient force to enter the point of the nail into the work a sufficient distance to support the nail, after which the hammer head is swung slightly to the left, the entered nail being held stationary by the work, so that the wider portion of the slot 32 is brought beneath the head of the nail, permitting the hammer to be raised away from the nail, and its driving continued, with the face of the hammer in the ordinary way.

In Figs. 10 and following of the drawings, there is illustrated another embodiment of the invention which may be considered preferable, under some circumstances, this device being arranged in two hingedly connected parts which may be swung upon their pivots to open the device and expose the various working parts, so that it may be quickly cleaned or repaired.

The handle body 40 of the second form of device is formed with a reservoir recess 41 at the outer part opening on the inner side face of the section, as well as on the 5 end of the handle, the side of the reservoir being closed by a cover section pivoted at the forward or poll end of the section 40. A blade 43 and face block 44 are carried by the handle section either integral or attached 10 thereto, as found most practicable. A feed recess 45 is formed in the forward part of the handle leading from the discharge opening of the reservoir 41, and forming a lateral extension of a larger recess 46. The 15 recess 46 opens upon the inner and lower sides of the handle section and has set therein a feed block 47 bifurcated to form a feed slot 48 therein, one side of the block being shorter than the other to form a lateral 20 outlet passage 49, the edge portion of the block abutting on the slot and passage being suitably cut away to permit the ready passage of a nail head, the slot 48, however, being only wide enough to permit free movement 25 of the nail shanks therethrough. In order to accommodate nails of greater length, the feed block may be extended laterally from the handle a distance toward the hammer face as at 50. The cover section 42 has a 30 hinged or other connection with the handle section 40 as indicated at 51, and a T-shaped trigger plate 52 is slidably mounted in the cover section in the same manner as before described, excepting that no lug is formed 35 on the plate for limiting its movement, which is accomplished by engagement of the trigger plate with the ends of the slot in which it is set, or engagement of the trigger proper with the ends of the slot in 40 the handle cover through which the trigger is projected. A short distance inwardly of the passage 49, a nail receiving slot 54 is formed in the cover section 42 adapted to align with the nail slot 53 of the trigger 45 plate when the trigger plate is at the rear limit of its movement. This slot opens at its outer side upon a circular discharge feed passage 54' formed within the cover section 42 and leading toward the hammer face. 50 Below the slot 53 of the trigger plate, a lateral extension 55 is formed on the head of the trigger plate projected outwardly through a slot 56 opening through the side of the feed passage 54', so that the member 55 may project across this passage at times 55 for engagement upon a nail head to drive the same. This extension 55 clears the passage 54' when the trigger plate is at the forward limit of its movement. Extending 60 across the passage 54' a short distance below the slot 56, there is a resilient device 58 to engage under and support the head of a nail yieldably against passage outwardly from the hammer. The hammer face is located at a distance below the slot 56 and ex-

tension 55 to permit the end of a nail to project from the hammer face when the head of the nail engages the extension 55. The resilient device 58 in the present instance, comprises a short length of rubber 70 elastic, although any other suitable yielding supporting device may be employed.

In the use of this form of device, when properly supplied with nails and manipulated to present nails in the passage 49, by 75 turning the hammer to the right when held in driving position or giving it a slight abrupt movement in that direction, a nail will pass into the nail slot 53 of the trigger plate, and upon drawing rearwardly upon 80 the trigger, the nail will be moved into position to pass through the slot 54 into the passage 55 whence it will drop into position with the head resting upon the resilient support 58 after release of the trigger. 85 Prior to release of the trigger the extension 56 of the trigger will support the nail. When it is desired for the nail to be projected from the face of the hammer, the trigger is released, the trigger plate moving 90 into position to receive another nail from the passage 49, and in order to drive the nail previously released and presented through the face of the hammer, the trigger is again drawn rearwardly, bringing the extension 95 56 over the head of the protruded nail. At the same time by delivering one forcible blow with the hammer while the nail is projected from the lower part of the passage 55 to fix the nail in the work, raising 100 of the hammer will leave the nail in the work owing to the yielding nature of the support 58. Driving of this nail may then be continued, pressure being maintained on the trigger to hold the trigger plate at its 105 rear limit of movement to prevent projection of a succeeding nail upon the hammer face, and upon release of the trigger a new nail will fall through the passage 55 into position for driving, allowing a repetition 110 of the operation described, as long as it is desired to continue the driving of nails, or the supply in the reservoir continues.

If desired, the passage 54' may open through the outer face of the cover section, 115 and be closed by a door plate 60, thereby enabling ready access to the discharge passage in case it should be necessary.

What is claimed:

1. A device of the character described 120 comprising a hammer having a nail reservoir, nail ordering means associated therewith, a guide-way leading therefrom formed in the hammer and having a lateral delivery part, an offset discharge slot being 125 formed in the hammer, adjacent said delivery part of the first named slot, a trigger constructed to close said delivery slot at one position and movable to engage a nail in the delivery slot to shift the same to said 130

discharge slot, said discharge slot including means to releasably engage a nail while in driving position.

2. A nail driving appliance comprising a reservoir element and nail duct leading therefrom having a terminal head, said duct having a longitudinal slot opening therefrom of a size to receive loosely the shank of a nail, said slot terminating in said head, a discharge slot offset from said termination formed in the head, a nail shifter reciprocable in the head across the two slots last named and having a nail shaped slot therein movable to alternately align with the slots and means in the discharge slot to releasably hold a nail head, said shifter having a portion disposed to lie over the nail head in said last named slot while in driving position.
3. A magazine hammer comprising a handle and head portion, said handle having a feed slot extending longitudinally therein, a magazine device arranged to feed to said slot, a trigger plate longitudinally reciprocable in the handle and having a part extended into the head, said feed slot being arranged to discharge to said plate, said plate having a nail-shaped slot therein adapted to receive a nail from the first named slot, a second slot in the hammer head, positioned to align with the slot in said plate at one limit of the movement of the trigger plate, resilient means to hold the trigger plate at one limit of its movement, and a trigger piece projected therefrom and from the side of the handle, said devices including means to releasably hold a nail at the outer part of said second named slot in the head.
4. In a magazine hammer, a hammer body including a handle and head, said handle having a nail ordering slot therein leading to the head and formed with a lateral terminal part in the head, a trigger plate slidable over the terminal end of the slot and having a nail receiving slot positioned to align with the terminal slot at one position, a second slot in the head offset from the first and open on the driving face of the head, said trigger plate being movable to align the nail receiving slot with said discharge slot in the head, means to

operate the trigger plate, and means to releasably engage a nail in the head at the outer part of the discharge slot, said trigger having a lug movable to extend across the discharge slot close above a nail engaged by said holding means.

5. A hammer of the character described comprising a body having a handle portion and head portion formed in two parts, divided near the major plane of the handle and head, a nail feeding slot formed in the handle portion of one section, a nail shank guiding block set removably in said section beside the slot and bifurcated to receive the shanks of nails slidably therein, one furcation being shorter than the other, said section being recessed in the block, the recess being the full length of the block including its longer furcations, whereby the short furcation will stop short of one end of the recess, a cover section of the hammer having a T-shaped recess therein, a T-shaped trigger plate slideable therein having a nail shaped slot adapted to align with the space at the end of said short furcation at one position of the trigger plate, yielding means to hold the trigger plate at one limit of its movement, a nail receiving slot being formed in the second section of the hammer inwardly of the trigger part when in initial position, communicating with said T-shaped recess whereby to receive from said trigger slot a nail at times, said slot in the second section of the hammer extended to the hammer face of the head, and means to releasably engage a nail head in the last named slot in position with its point projected from the inner face, said trigger having a part positioned to engage across the last named slot above an engaged nail head at one position of the trigger plate, said trigger plate having a lug thereon to project through the side of said slot in the second section and reciprocable longitudinally thereacross.

In testimony whereof I have affixed my signature in presence of two witnesses.

JAY CRUMPACKER.
